UNITED STATES PATENT OFFICE.

ROBERT COLLEN, OF LONDON, ENGLAND.

TRUSSING-MACHINE.

SPECIFICATION forming part of Letters Patent No. 613,247, dated November 1, 1898.

Application filed December 24, 1897. Serial No. 663,367. (No model.)

To all whom it may concern:

Be it known that I, ROBERT COLLEN, engineer, a subject of the Queen of Great Britain and Ireland, residing at 30 Pigott street, Limehouse, in the city of London, England, have invented certain Improvements in Trussing-Machines, of which the following is a specification.

This invention relates to trussing-machines of the type known as "open-trussing" machines, in which the staves are contracted or forced together by the aid of trussing-hoops preparatory to their being more tightly forced together in what are known as "close-trussing" machines.

I will describe the invention by reference to the accompanying drawings, in which—

Figures 1 and 2 are respectively a front and a side elevation of one of my improved trussing-machines.

The main framing of this machine consists of a base A, two standards or guides B B², secured at their lower ends to the base, and a girder C, secured to the upper ends of the guides B B². The hydraulic cylinder D is rigidly secured to the girder C, and the piston-rod D², issuing therefrom, is secured to a fork or yoke E, connected to blocks E², capable of sliding vertically in the guides B B².

In the blocks E² (in accordance with a separate application for Letters Patent of even date herewith) is pivoted a reversible head or double cone F, by which the upper ends of the staves are forced together, and the two trussing-hoops contained in the said head are passed over these stave ends. My present improvements, however, may, if desired, be used in conjunction with a single or non-reversible cone. The two ends of the cylinder

D are connected by pipes d d², respectively, with the ports g g², Fig. 2, of a valve G, which is constructed, preferably, like an ordinary D slide-valve, the movable valve of which may be operated to throw either of the said ports into communication either with the inlet g³, connected with the pressure-supply apparatus, or with the exhaust g⁴, which is connected with a tank H, supported on the girder C. The valve G may be operated through a link g⁵, a lever g⁶, pivoted in a standard g⁷, a rod g⁸, and a hand-lever g⁹, pivoted to the before-mentioned guide B². The rod g⁸ passes

through a bracket e, secured to the block E², which slides in the guide B², and on the rod g⁸ is provided an adjustable collar g¹⁰, with 55 which the bracket e engages, and thereby cuts off the supply of pressure-water when the cone F has ascended sufficiently to admit of the casks being inserted into or removed from the machine. The collar g¹⁰ is adjusted on 60 the rod g⁸ to suit the different heights of the casks to be operated upon, so that the pressure-water may not be wasted by employing it for raising the cone beyond the necessary height.

To the before-mentioned pipe d is connected a pipe d³, which extends down to near the bottom of the tank H, at which part it is provided with a suction-valve d⁴, which closes when exposed to the influence of the pressure-water—that is to say, when the pipe d is in communication with the supply-pipe g⁸. 65 The valve d⁴ opens when the communication between the pipes d and g³ is broken and the communication between the pipes d² and g⁴ 70 is established, so that the cone F and the parts directly connected therewith may descend by gravity, the water during this operation passing from the tank H through the pipes d³ and d into the upper end of the cylinder and from the lower end of the cylinder 75 into the tank by way of the pipes d² and g⁴. When the cone F has descended to the part 80 of its travel at which it is required to force the staves together, the attendant raises the hand-lever g⁹, and thereby allows the pressure-water to enter the upper part of the cylinder 85 to enable the cone to complete the short remaining portion of its downward stroke.

At its upper part the tank H has connected 90 to it a pipe h, which may conduct the water which overflows from the said tank back to the waste-water tank, from which the pumps or other pressure-generating devices draw their supply. The tank H also has an air- 95 inlet at h² to prevent the formation of vacuum.

To prevent any water which may leak through the stuffing-box d⁵ of the cylinder D from descending onto the casks, I provide the yoke E with a cup e², to which is connected 100 a pipe e³, which conducts the said water to the side of the machine, where it may be delivered into any desired receptacle.

Although I have shown the tank H at the

side of the cylinder D, which is the most suitable position for it, I may arrange it either higher or lower than the said cylinder.

Having now particularly described and ascertained the nature of my said invention and in what manner the same is to be performed, I declare that what I claim is—

1. In a trussing-machine the combination with a cone and a frame with vertical guides for the cone, of an inverted hydraulic cylinder on the frame, a piston in the cylinder connected to the cone, a tank, a pipe connecting the cylinder-exhaust with the tank, a pipe connected with the upper end of the cylinder and dipping into the tank, a valve on the end of this pipe, an overflow-pipe for the tank, a

cup on the piston-rod and a pipe connected to the cup and leading to outside the machine substantially as set forth.

2. In a trussing-machine the combination with an inverted hydraulic cylinder of a tank, a pipe connecting the cylinder-exhaust with the tank and a valved pipe connected with the upper end of the cylinder and dipping into the tank substantially as set forth. 25

In testimony whereof I have signed my name to this specification in the presence of two subscribing witnesses.

R. COLLEN.
